CLAIM

The ornamental design for a campsite comfort portable chair/toilet seat, as shown and described.

DESCRIPTION

FIG. 1 is a top plan view of my design with the seat top shown in an open position;

FIG. 2 is a top plan view, with the seat top shown in the closed position, the legs shown broken away for ease of illustration;

FIG. 3 is a side elevation view, the opposite side being a mirror image thereof; and,

FIG. 4 is a front elevation view, the legs shown broken away for ease of illustration.

The broken line showings of hook and loop fasteners in the drawings are for illustrative purposes only and form no part of the claimed design.
